UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

GRID FOR GAS BURNERS.

Application filed June 30, 1925. Serial No. 40,523.

To all whom it may concern:

Be it known that I, JOSEPH ROY, a citizen of the United States, residing at Cleveland, in the county of Cuyahoga and State of Ohio, have invented certain new and useful Improvements in Grids for Gas Burners, of which the following is a specification, reference being had therein to the accompanying drawing.

10 This invention relates to improvements in grids for gas burners and is intended for use in various types of burners.

The primary object of the present invention is to simplify the construction of a gas burner grid.

A further object is to decrease the cost of producing a gas burner grid, and at the same time make it accurate in construction and efficient in operation.

20 A further object of the present invention is to make a gas burner grid with vertically arranged spaced bars connected by narrow integral parts of metal from which the grid is constructed.

25 A further object of the present invention is to produce a gas burner grid with vertically arranged spaced bars connected with transversely narrow arranged parts made from the same metal, the bars arranged longitudinal the burner body, whereby efficiency in operation, accuracy in construction, and cheapness in production are all accomplished.

30 A further object of the present invention is to make an improved gas burner grid by stamping openings in a line from a sheet, then bending the sheet at the junction of the openings and compressing the bent sheet, the walls of the opening thus forming transverse connections for the vertical bars.

35 A further object of the present invention is to form a gas burner grid by cutting in a suitable sized sheet several rows of openings arranged in a line, one wall of the openings bent at its junction with the other walls of the openings, and then compressed until the bent portions are brought in contact with each other, whereby aligned vertical separated bars are formed, the bars being connected by the bent walls of the

Further objects of the invention will appear from the following description.

In the drawings:

Fig. 1 is a top plan view of a radiant heat burner showing my improved grids applied thereto.

Fig. 2 is a plan view of a different type of burner showing the improved grid applied to it.

Fig. 3 shows a sheet with openings cut in it which is the first step in the production of this improved grid.

Fig. 4 shows an edge elevation of the sheet bent.

Fig. 5 is a top plan view of Fig. 4.

Fig. 6 is an enlarged transverse sectional view of Figures 4 and 5.

Fig. 7 is an enlarged plan view of the improved grid.

Fig. 8 is an edge elevation of Fig. 7.

Fig. 9 is a cross sectional view on the line 9—9 of Fig. 7.

Fig. 10 is an enlarged longitudinal view of the bent sheet before it is compressed into final form.

Fig. 11 is a side elevation of the improved grid bent at different points from that shown in Figs. 7, 8 and 9.

Fig. 12 is a cross sectional view on the line 12—12 of Fig. 11.

Fig. 13 is a perspective view of one end of the improved grid.

Referring now to the accompanying drawings, it will be noted that when the grid is used for a radiant heat burner that it is composed of a plurality of sections 1, 2, 3, 4 and 5. These sections are properly set in the open top of a housing 6, and the several sections are held in position by suitable members 7, that are located between the ends of the sections and suitable screws 8 that pass through the members 7 into the housing 6. I desire it understood that the number of sections may be varied and the manner of connecting the sections may be different from that here shown without departing from the present invention.

In fact in Figure 2 I show a top burner 9 for gas ranges which has a housing provided with a plurality of radially extending members 10 to which the improved grid 11 is suitably attached.

This improved grid is adapted not only for connection with the two types of burners already mentioned, but is adapted for use in connection with gas range ovens and broilers etc. and therefore the use of the grid is not to be limited.

In producing this improved grid I take a suitably sized sheet of metal as shown in Fig. 3, and stamp in the sheet a plurality of openings 12. Preferably the sheet is elongated, and the openings therein are arranged in lines transverse and longitudinal of the sheet, and the said openings are rectangular in form and considerably wider than the walls 13 and 14 that form said openings. The walls 14 of these openings 12 are bent substantially at their junctions 15 with walls 13. When bent the metal sheet then is in substantially the form shown in the end view Fig. 4 and the top plan view Fig. 5. Figure 6 is an enlarged view of the sheet bent as shown in Figures 4 and 5, which shows that the bend is substantially at the junction of the wall 14 with the wall 13 at 15.

The sheet having been bent as disclosed in Figures 4 to 6 inclusive, is then tightly compressed until the doubled portions are in contact with each other as shown in Figure 9 which produces a grid constructed as shown in Figure 7.

This grid when made up has its walls doubled upon each other, thereby forming longitudinal spaces 16 that extend between the connecting doubled walls 13 of the grid.

The walls 14 are doubled while the walls 13 stand on end in separated relation forming the longitudinal spaces 16 that are located between the doubled parts 14.

By reference to Figure 8 it will be observed that by doubling the walls 14 substantially at their junction with the walls 13 that the doubled part extends only slightly above the bars 13 as shown at 17, Fig. 3, whereas the lower doubled part of the grid extends considerably below the walls 13 as shown at 18, Fig. 8.

The object of forming the grid as shown in Figs. 7, 8 and 9 is to prevent any appreciable amount of metal extending above the top of the grid and therefore in the combustion, because it would become heated and would have a tendency to fire back between the separated walls 13. However in some constructions it might be desirable to make the bend further removed from the junction of the walls 13 and 14, for instance as shown in Fig. 10 which would produce a grid in side elevation as shown in Fig. 11, whereby the doubled portions of the walls extend equal distances or substantially equal distances below and above the upper and lower edges of the walls 13. It will be readily understood that the distance that the doubled portion of the walls 14 extend above or

below the edges of the walls 13 can be regulated by the point at which the walls 14 are doubled.

It will be observed from the foregoing description of this improved grid that the doubled portions 14 extend transverse the grid when completed, and that the walls 13 extend longitudinal the grid, consequently causing the said walls to stand endwise and form longitudinal spaces 16 for the passage of the fuel between the doubled parts 14.

From the foregoing I produce a grid which is simple in construction because it is made from a single sheet of perforated metal.

I produce a grid which is accurate in its formation because the spaces 16 between the vertical bars are accurately formed by reason of the bars being bent until they are in contact with each other thus making uniform spaces. It produces a grid which is efficient in operation because it is accurate, and enables all of the grids to be made with equal spaces between the vertical bars for feeding the fuel thus avoiding inefficiency which arises from unequal spaces between the vertical bars.

It will be understood that the spaces between the vertical bars are regulated by the thickness of the sheet, thus enabling the spaces to be accurately made to suit the work that is to be performed by the grid.

I do not limit myself to the exact construction herein shown and described, because various changes might be made without departing from the spirit and scope of the invention so long as it is within a fair interpretation of the appended claims.

Having thus described my invention what I claim and desire to secure by Letters Patent is:—

1. A gas burner grid comprising a plurality of parallel vertical bars spaced apart by vertical strips passing between the said bars, the strips having their upper and lower edges connected with the upper and lower edges of the said bars.

2. A gas burner grid comprising a plurality of vertically arranged bars spaced apart by vertical strips passing between the said bars, the tops of the strips connected with the top of one bar, and the lower end of the strips connected with the bottom of an adjacent bar.

3. An improved gas burner grid comprising vertically arranged parallel spaced bars, and vertically arranged strips passing between the said bars, the said strips having their upper ends bent and integral with the upper edges of one bar and the lower end of the strip bent and integrally connected with the lower edge of an adjacent bar.

4. An improved grid for gas burners, comprising a plurality of vertically arranged bars, said bars having integral

- transversely arranged portions located at their upper and lower edges, said transverse portions being bent and connecting and sustaining the upper and lower edges of the 5 bars in uniform spaced relation.
5. An improved grid for gas burners, comprising a plurality of vertically arranged bars, said bars having a plurality of transversely arranged portions, said portions arranged in spaced relation, said portions holding the bars in uniform spaced relation and the portions forming obstructions for the passage of gas thereby the grid having a plurality of burning spaces. 10
15. An improved grid for gas burners, comprising a plurality of vertically arranged bars, said bars having transversely arranged integral portions at their upper and lower edges, the portions at their upper 20 edges being bent downward and at their lower edges bent upward, thus sustaining the bars in uniform separated relation.
7. An improved grid for gas burners comprising a plurality of vertically arranged 25 bars spaced apart by vertical strips and arranged in a plurality of transverse lines, the opposite ends of the said strips connecting and holding the said bars whereby a grid is formed with a plurality of separate 30 spaces for the passage of gas for the purpose specified.
8. An improved grid for gas burners comprising a plurality of vertical parallel bars separated by vertical strips which are arranged in parallel spaced lines for the 35 purpose described, the upper ends of the strips secured to the upper portion of one bar and the lower end secured to the lower portion of an adjacent bar.
9. An improved grid for gas burners 40 comprising a plurality of parallel vertical bars separated by vertical strips, the upper ends of the strips connected to the top portion of one bar and extending down considerably below the lower edges of the bars 45 with their lower ends connected to the lower portions of adjacent bars.
10. An improved grid for gas burners comprising a plurality of vertical parallel bars connected by integral strips passing 50 between the said bars, the upper ends of the strips bent closely to and integrally formed with the upper parts of the bars and the lower ends of the strips extending considerably below the said bars and doubled upward with their ends connected with the lower parts of adjacent bars for the 55 purpose described.

In testimony whereof he hereunto affixes his signature.

JOSEPH ROY.
